(57) **CLAIM**

The ornamental design for an openings for incontinence pant, as shown and described.

DESCRIPTION

FIG. 1 is a front elevational view of an incontinence pant, according to our new design;

FIG. 2 is a rear elevational thereof;

FIG. 3 is a right side elevational view thereof; and,

FIG. 4 is a left side elevational view thereof.

All portions shown in broken lines are for illustrative purposes only and form no part of the claimed designs.

1 Claim, 2 Drawing Sheets

FIG. 3

FIG. 4
